[57] CLAIM

The ornamental design for combined storage unit and holder for a juicer and grater, as shown and described.

DESCRIPTION

FIG. 1 is a perspective view of the combined storage unit and holder for a juicer and grater showing our new design;

FIG. 2 is a top plan view thereof;

FIG. 3 is a front elevational view thereof;

FIG. 4 is a right side elevational view thereof, the opposite side being identical; and,

FIG. 5 is a rear elevational view thereof.

The undisclosed bottom view is flat and unornamented.
